UNITED STATES PATENT OFFICE.

JOSEPH B. ARMITAGE, OF PAWTUCKET, RHODE ISLAND, ASSIGNOR TO NARRAGANSETT MACHINE COMPANY, OF PAWTUCKET, RHODE ISLAND, A CORPORATION OF RHODE ISLAND.

VAULTING HORSE-BUCK.

1,128,832.

Specification of Letters Patent. Patented Feb. 16, 1915.

Application filed January 24, 1914. Serial No. 814,207.

To all whom it may concern:

Be it known that I, JOSEPH B. ARMITAGE, a citizen of the United States, residing at Pawtucket, in the county of Providence and 5 State of Rhode Island, have invented a new and useful Improvement in Vaulting Horse-Bucks, of which the following is a specification.

This invention relates to certain new and 10 useful improvements in vaulting horse bucks and relates more particularly to the means for causing engagement of the casters with the floor to enable the apparatus to be moved from one place to another in the gymna- 15 sium.

The primary object of the invention is to provide means whereby the casters may be moved from a point at the top of the apparatus to engage the floor without any move- 20 ment of the top of the horse buck independent of the entire structure and to also enable the casters to be moved to engage the floor regardless of the position of the top of the horse buck, *i. e.*, whether said top is in 25 high or low position.

A further object of the invention is to provide means which is permanently and at all times in position ready for actuation to cause engagement of the casters with the 30 floor.

A still further object of the invention is to provide caster actuating means which is coupled with the raising and lowering means of the horse buck top, so that the movement 35 of the latter positively effects variation of movement of the caster actuating means so as to maintain the latter in position ready for operation throughout any and all positions or range of elevations which the top 40 of the horse buck is capable of having.

In the drawings—Figure 1 is a fragmentary vertical sectional view of the top part of a horse buck embodying the present invention. Fig. 2 is a fragmentary vertical 45 sectional view of the bottom part of the horse buck. Fig. 3 is a fragmentary detail view. Fig. 4 is a side elevation, partly in vertical section of the complete invention, and Fig. 5 is a detail view.

50 The base 1 has hollow ends, and also has a vertical column 2 thereon, which latter receives on its interior the hollow depending stem 3 of the top 4. A shoe 5 is pivoted at 6 to the base 1 and carries a caster 7, the 55 shoe and caster when the apparatus is be-

ing used for exercising purpose being received within the base so as to allow the latter to directly engage with or seat on the floor as depicted in Fig. 2 of the drawings.

Rigidly secured to the base 1 and projecting upwardly therefrom is an interiorly threaded tubular post 8, into which extends and engages the lower threaded end of a rod 9. The rod 9 is connected to the top 4 and is rotatably mounted in a bearing 10 formed on the head 11 of the stem 3, the head 11 being rigidly connected to the top 4 in any suitable manner. A cap 12 is affixed to the upper end of rod 9 and sets on the upper end of the bearing 10. For 70 the purpose of preventing upward movement of the rod 9, a thrust ball bearing 13 is interposed between the under face of head 11 and the upper end of a gear 14 which latter is rigidly secured to rod 9. 75 Rods 9 are operated by any suitable means, common to horse bucks and upon rotation will raise or lower the top 4, as desired, through the rods 9 and the posts 8.

For the purpose of engaging the shoe 5 so 80 as to lift the base 1 up from the floor, a pair of rods 15 are provided which rods have their lower ends connected to a coupling 16, to the lower end of which latter a rod 15' is secured, the rod 15' bearing against set 85 screw 17 which is carried by the shoe. The rods 15 are slidably guided in apertures provided therefor in a head 18 formed on the upper end of the post 8. A cross head 19 connects the upper ends of the rods 15 and has a central threaded bore through which passes a threaded rod 20, the rod 20 having a gear 21 on its upper end portion which meshes with the gear 14 of the rod 9, the gear 14 being of such length that same 90 will remain in mesh with the gear 21 throughout the sliding movements of rod 20 which carries gear 21 in its up and down movements. The stationary post 8 by virtue 95 of its head 18 engaging the pair of rods 15 prevents rotating movement of the latter.

It will be understood that all of the mechanism above described is duplicated at each end of the apparatus.

A rotary disk or member 22 is carried by 105 the top 4 of the horse buck and has the curved ends of a pair of levers 23 pivotally secured to diametrically opposed points thereon, the handle 24 being connected to member 22 whereby to rotate same. A bell 110

crank lever 25 is pivotally secured at 26 to the head 11 of stem 3 and has one arm pivoted to the adjacent lever 23 and its other arm bearing on the upper end of rod 20.

5 In operation, downward movement of handle 24 causes outward movement of the levers 23 and therewith outward movement of the vertical arms of the bell cranks and downward movement of the horizontal arms 10 of the bell cranks the latter exerting downward pressure on the rods 20 and since the latter are connected to the rods 15 by the cross head 19, the rods 15 will be depressed to cause rods 15' to exert pressure on the set 15 screws 17 of the shoes 5, thus effecting raising of the base 1 relative to the floor, bringing the casters into operative position. In rotating the rod 9 so as to raise or lower the top of the horse buck, gear 14 by virtue 20 of meshing with gear 21 will rotate the latter and thereby the rod 20, the latter causing corresponding up or down movement of cross head 19 and rods 15, thus at all times maintaining the rods in engagement with the shoe, whereby when the bell cranks exert pressure on said rods 15 the base 1 will 25 be raised up free of engagement with the floor.

It is particularly to be noted that the 30 present invention enables the apparatus to be moved up from the floor from the top thereof, and it is further to be observed that the entire means for effecting lifting up of the base from the floor is concealed from view.

Having thus described my invention, I claim as new and desire to secure by Letters Patent:—

1. In combination with a base and the top 40 of a vaulting buck and an adjustable connection between same consisting of a rigid tubular threaded post on the base and a threaded rod therein depending from the top, a pivoted caster carrying shoe, carried 45 by the base, a perforated head on said post, a pair of rods slidingly arranged in said perforations, a cross head connected to the upper ends of pair of rods and having a threaded aperture, a threaded rod in said 50 aperture, a member carried by the top which slidably supports said last named rod, intermeshing gears between the first and last named rods, a bell crank lever pivoted to said member and having its horizontal arm 55 engaged with the upper end of the last named rod, a lever pivoted to the vertical arm of the bell crank, and means to actuate the lever.

2. In combination with a base and the top 60 of a vaulting buck and an adjustable connection between the two including a rotatable member, a caster movable relative to the base, means to engage the caster to thereby enable the base to be raised relative to the 65 caster, means actuated by the rotatable mem-

ber to simultaneously operate the caster engaging means so as to maintain same in position ready for operation throughout the movements of said rotatable member, and means independent of the rotatable member 70 to actuate the caster engaging means.

3. In a vaulting horse buck, in combination with a base and a top, means including a rotary element to adjust the space between the base and top, a caster movable relative to 75 the base, means between the caster and top to enable actuation of the caster from the top, means to operate said last named from the rotary element to cause same to maintain engagement with the caster throughout 80 the up and down movements of the top, and means independent of the rotary element to actuate said caster engaging means.

4. In a vaulting horse buck, in combination with a base and a top and means to vary the 85 space therebetween, a caster movable relatively to the base, means between the caster and top to raise the base relative to the caster, means operated by the means for varying the space between the base and top 90 for maintaining said second named means in position ready for operation regardless of the relative positions of the base and top and means independent of the first named means for operating the base raising means. 95

5. In a vaulting horse buck, in combination with a base and a top and means to vary the space therebetween, caster bearing means movably carried by the base, means between the top and the caster bearing 100 means engaged with the latter to raise the base from the floor, means to actuate said raising means, and means whereby said raising means is always maintained in engagement with the caster bearing means regardless of the up and down movements of the top. 105

6. In a vaulting horse buck, in combination with a base and a top and means to vary the space therebetween, a caster movable relatively to the base, an extensible and contractible device between the top and base engaged with the caster, means to engage said device to raise the base up from the floor, and means to operate said caster engaging means independent of the first named means, means operated by the first named means to actuate said device so as to always maintain the latter in engagement with the caster throughout the movements 115 of the first named means. 120

7. In a vaulting horse buck, in combination with a base and a top, and means to vary the space between the same, a caster carrier at each end of and movable relative 125 to the base, separate means carried by the top to engage each of said carriers to allow raising of the base relative to the casters, means for maintaining engagement between each carrier and the raising means thereof, 130

and means carried by the top for engagement with each of said raising means to actuate same in unison.

8. In a vaulting horse buck, in combination with a base and a top, and means to vary the space between the same, a caster carrier at and movably connected to each end of the base, a contractible and expansible device for each carrier engaged therewith and connected with the top, means to actuate said devices from the first named means to maintain the device in position for engaging the carriers, and means for actuating each device in unison to effect raising of the base relative to the casters.

9. In a horse buck, in combination with a

base and a top, a caster carrier connected to the base, means to engage the carrier, means to raise and lower the top and to also maintain said carrier engaging means in position to actuate the carrier, and means independent of the raising and lowering means to actuate the carrier engaging means to raise the base relative to the caster.

In testimony whereof I have signed my name to this specification in the presence of two subscribing witnesses.
